UNITED STATES PATENT OFFICE.

THOMAS CONNELL, OF IOWA CITY, IOWA.

DAMPER-REGULATOR.

1,257,190.

Specification of Letters Patent. Patented Feb. 19, 1918.

Application filed November 2, 1916. Serial No. 129,208.

To all whom it may concern:

Be it known that I, THOMAS CONNELL, a citizen of the United States, and resident of Iowa City, in the county of Johnson and State of Iowa, have invented a certain new and useful Damper-Regulator, of which the following is a specification.

The object of my invention is to provide a damper regulator of simple, durable, and inexpensive construction.

A further object is to provide such a device especially adapted for installation on boilers of heating systems of the vapor type.

A further object is to provide a means whereby appropriate dampers may be lowered and raised automatically when the pressure in the boiler becomes less or greater.

A further object is to provide such a device having means for indicating boiler pressure which also show whether the regulator is being properly operated by the pressure in the boiler.

A further object is to provide a damper regulator operating said dampers by a movable arm, and to provide suitable devices to limit the movement of the arm in either direction.

A still further object is to provide a rigid passage between a water chamber and a tank on the regulator arm.

My invention consists in the construction, arrangement, and combination of the various parts of the device, whereby the objects contemplated are attained, as hereinafter more fully set forth, pointed out in my claims, and illustrated in the accompanying drawings, in which:

Figure 1 shows a front elevation of a boiler having a damper regulator attached thereto which embodies my invention.

Fig. 2 shows a front elevation of the device with certain parts in section to better illustrate the construction, and,

Fig. 3 shows a side elevation with parts broken away.

Referring to the accompanying drawings, I have used the reference numeral 10 to indicate generally a boiler of ordinary construction, having damper 11 and check draft 12 mounted thereon, the damper and check draft being preferably arranged to be opened by a pull on a chain and to be closed by gravity when the chain is loosened.

An upright 13 is fixed to the floor adjacent to the boiler or to the top of the boiler, and extends to a point above the water level in

the boiler, where it supports a liquid tight chamber 14, the latter being preferably rectangular in shape. A pipe 15 is adapted to conduct the vapor in the boiler to the top of the chamber 14, and a second pipe 16 conducts back to the boiler the over flow from the chamber when the water therein reaches a point near the top. The pipe 16 is arranged to discharge into the pipe 15 at a point below the water line in the chamber so that it will not be necessary to have two openings into the boiler to attach my device thereto.

A bushing 18 is screwed into the opening 17 in the upper part of one of the sides of the chamber, the bushing being provided with a bearing at its outer end. A second bushing 19 is screwed into the inner end of the bushing 18 a sufficient distance to allow space for packing 20 between the bearing on bushing 18 and the adjacent end of bushing 19.

A tube 21 is journaled in the bushings 18 and 19 and screw threaded at its outer end, the inner end being bent at right angles to the portion in the bearings and extending downwardly to a point adjacent to the bottom of the chamber. Collars 33 are fixed to the tube 21 to prevent it from sliding longitudinally in said bearings.

A T 22 is screwed to the outer end of the tube 21, a partition 23 being formed therein adapted to prevent the liquid in said tube from entering one of the branches in the T.

An arm 24 is fixed into the closed branch of the T, said arm having a weight slidably mounted thereon, a set screw 34 being adapted to coact with arm 24 to hold the weight in any desired place on the latter. A tube 26 of substantially the same length as arm 24 is screwed into the other branch of the T, and extends in the opposite direction from said arm, the tube 26 having a tank 27 fixed to its outer end and communicating with the inside of the tube. The tank 27 is provided with vent 35 in the top thereof, and rings 28 and 29 are fixed to its outer, upper and lower edges respectively.

A chain 30 operatively connects the ring 28 with the check draft 12, and a chain 31 connects ring 29 with damper 11.

The parts are so arranged that when there is no liquid in the tank 27, the weight of the ball 25 will move the tank upwardly, thereby loosening the chain 30, so that the check draft will be closed, and pulling the chain 31

sufficiently to open damper 11. When in this position, the tank should be some distance above the water level in the chamber 14, so that the tank may move downwardly a sufficient distance to have a contrary effect on the position of the damper and check draft before reaching a position where the bottom of the tank is level with the water level in the chamber.

10 Three bolts 36 have their ends screwed into the side of the chamber 14 through which tube 21 extends, one being spaced below said tube and the other two being spaced equally distant horizontally from the first. A plate 37 is pivoted on the central bolt 36 and provided with curved slots 38 through which the other bolts 36 project, thereby limiting its pivotal movement. Lugs 39 and 40 extend laterally from the upper corners of plate 37 and have threaded openings therein adapted to receive bolts 41 and 42. A spring 43 encircles the bolt 41 and engages the lug 39 and the tube 26 to hold them yieldingly separated.

25 A pet cock 44 is adapted to drain the chamber 14 when desired. A pressure gage 32 communicates with the top and bottom of chamber 14 and has valves at each end to allow operation of the regulator temporarily. Rarely should the glass of the gage break. A pet cock 45 is adapted to drain the gage when desired.

In the practical operation of my device, the bushing 19 is screwed into the bushing 18 until the packing 20 is squeezed tightly enough around the tube 21 to make a liquid and gas tight joint. Sufficient fire is then made in the boiler to bring the vapor therein to approximately the desired pressure.

40 My regulator will cause the damper to remain open until the vapor reaches a predetermined pressure, when the water in the chamber 14, which by means of the pipe 15 is kept under the same pressure as the boiler, will be forced by such pressure up into the tank 27 through tube 21 and its connections until enough water accumulates in said tank to counterbalance weight 25, thereby lowering said tank until the damper 11 closes on account of the loosening of chain 31, and check draft 12 will be opened by the consequent tightening of chain 30.

It will be understood that water enough to operate the device may be placed in the chamber 14 when it is installed, or that condensation of the vapor received by it from the tube 15 will fill it to the overflow level after it has been used in connection with an operated boiler for a very short time.

55 The pressure gage operates through its connections with the top and bottom of the chamber to indicate the amount of water therein. This serves two purposes, for by the amount of water in the tube, it can be

determined at a glance if the device is working right, as for instance, if the overflow tube 16 or the vapor tube 15 should become stopped up, the operator could tell in a moment by a glance at the gage, for in the former case the water would fill the tube completely, and in the latter case the water would remain some distance below the overflow level although the tank 27 remained in its upper position. The gage is also graduated so that the difference in the water level due to some water in the chamber 14 being forced up into tank 27 by the pressure of the vapor, will indicate on the graduations what the pressure in the chamber is and consequently that of the boiler.

It will be understood that my device is constructed to employ the well known principle that a pressure of one pound per square inch will raise a column of water approximately two feet, and that therefore the pressure in the boiler may be changed by regulating the height at which the water in the tank 27 is raised by the pressure in the chamber 14, when the accumulated water in the former will counterbalance the weight, thereby changing the position of the tank and the damper and draft.

The plate 37 with bolts 41 and spring 43 operates to limit and regulate the movement of arms 24 and 26 by preventing movement of the latter through an arc greater than the length of the slots 36. By turning bolts 41 and 42, the compression on spring 43 may be adjusted to form a spring cushion for tank 27 when it reaches the downward limit of its movement. The sliding ball 25 on arm 24 allows a fine adjustment of the weight of water necessary to counterbalance the ball, with a consequent closer adjustment of the pressure in the boiler.

Some changes may be made in the arrangement and construction of the parts of my damper regulator, and it is my intention to cover by this application any such changes in the arrangement and construction which may be included within the reasonable scope of my claims.

I claim as my invention:

1. In a device of the class described, a support, a receptacle at one end thereof, designed to be in communication with a boiler, a tube rotatably mounted in the wall of said receptacle near the upper end thereof, a tube extending downwardly from the inner end of said first tube, a tube mounted on and communicating with said first tube having a partition on one side of the opening in said first tube, a receptacle mounted on said third tube and communicating therewith at the end thereof opposite said partition, and means for connecting said last described receptacle with draft regulating devices.

2. In a device of the class described, a re-

ceptacle, designed to be in communication with a boiler, a tube rotatably extended through the upper wall of said receptacle, a tube mounted on said first tube and communicating therewith, a weight on one end of said second tube, a receptacle on the other end of said second tube communicating therewith, a plate mounted below said rotatably mounted tube, having in its ends curved slots, said plate being pivotally supported, members secured to said first receptacle and extending through said slots, adjustable bolts carried by said plate designed to engage said second tube on opposite sides of its pivotal point.

3. In a device of the class described, a receptacle, designed to be in communication with a boiler, a tube rotatably extended

through the upper wall of said receptacle, a tube mounted on said first tube and communicating therewith, a weight on one end 20 of said second tube, a receptacle on the other end of said second tube communicating therewith, a plate mounted below said rotatably mounted tube, having in its ends curved slots, said plate being pivotally supported, members secured to said first receptacle and extending through said slots, adjustable bolts carried by said plate designed 25 to engage said second tube on opposite sides of its pivotal point, and a spring mounted 30 on the bolt nearest said second tube.

Des Moines, Iowa, October 25, 1916.

THOMAS CONNELL.
